United Shoe Machinery Corporation, Elmington,
N. J., a corporation of New Jersey

Application March 16, 1946, Serial No. 654,884

16 Claims (Cl. 12—1)

1

This invention relates to a machine for cementing shoe parts, and it is herein illustrated as embodied in a machine particularly intended for cementing the margin of a "platform cover." This application is a continuation in part of an application for United States Letters Patent Serial No. 551,681, filed August 29, 1944, in my name and now abandoned.

Shoes of the "slip-lasted" type are usually provided with a platform sole and/or a wedge heel and have a piece of flexible material extending around at least part of the periphery of the shoe. This material, called the "platform cover," is usually stitched to the upper and, considering the shoe in inverted position, is upturned to surround the periphery of the platform sole. Commonly, the platform cover is laid over the margin of the bottom of the platform sole and held in position by cement. Such soles are frequently of yieldable material which in itself requires that the platform cover be drawn tautly around the corner of the sole before it is laid over or lasted and held in place. Besides this, the platform cover material is frequently cloth and does not have a uniform stretch. Furthermore, the manner of sewing this piece of material to the upper is such that the cover material must be bent around the seam so formed as the cover is drawn over the periphery of the platform.

Many manufacturers prefer to apply cement to the sole itself before it is positioned upon the shoe and, when this is done, the application of cement to the cover is undertaken as it projects from the bottom of the shoe. A similar problem is encountered in the cementing of unlined uppers which are to be cement-lasted and in the cementing of certain moccasin uppers for cement-lasting. For greatest facility of manufacture this band of cement should extend almost as far as the corner of the platform sole, for example, and not farther, because, if cement gets in between the cover and the periphery of the platform sole, the two must be pulled apart before the cover can be satisfactorily lasted. On the other hand, it is desirable to have the cement lie close to the periphery of the platform sole because this will insure a firm bottom structure for the attachment of the outer sole.

One important object of the invention is to provide a machine which will apply cement to only that portion of the margin of the material which is to be lasted over the bottom of the shoe.

Another object of the invention is to provide a machine which simultaneously will tension the

projecting band of upper material and will apply a marginal stripe of cement thereto.

These objects are effected in the illustrated machine, and in accordance with features of the invention, by feeding the marginal band of projecting material between a coating applying roll and a supporting roll in a direction inclined to the axis of the applying roll and, hence, at an angle to the feeding force exerted by the rolls, thereby to create a wedging force which tensions and sometimes stretches the material being coated. The direction of movement of the material to be coated is determined by means of a work rest positioned at or in front of the free end of the cement applying roll to engage the bottom of the shoe. This work rest, which cooperates with the coating and feeding means to tension the marginal material, has a work-engaging surface parallel to the angular direction mentioned above and, in one form, it is provided by a wedge-shaped abutment supported at the end of the applying roll but separate therefrom.

Another feature of the invention resides in a machine having cover-coating and tensioning means which is provided with means interposed between the coating means and the platform sole, acting to space the band far enough from the corner of the sole so that contact of the coating with the peripheral edge of the sole is prevented even when the tension on the cover is relieved.

In accordance with another feature of the invention, the work rest comprises a smooth, conical button illustrated as attached to the end of the cement applying roll and against which the previously coated platform sole may be rested without disturbance of the surface thereof. Furthermore, and as illustrated, the base of the conical member is spaced a small fraction of an inch from the end of the applying roll to provide a clear margin between the band of cement and the corner of the platform sole.

With both this button rest and with the wedge-shaped abutment, one component of feeding force effectively stretches the flexible material and draws the bottom of the shoe up close to the end of the cement roll, whereby that width of the material which is coated will extend nearly up to, but not beyond, the corner of the platform sole.

These and other features of the invention will best be understood from a consideration of the following specification taken in connection with the accompanying drawings, in which

Fig. 1 is an angular view of the head of a cover-coating machine for latex-type cement with the

rolls in open position ready to receive the work;

Fig. 2 is a plan view showing a portion of a horizontally positioned shoe, partly in section, with its platform cover gripped between the rolls and with the bottom of the platform sole upright and resting against an abutment;

Fig. 3 is an elevation of the work-gripping rolls and shows a portion of the heel end of a shoe, partly in section with the shoe positioned toe end up and with the platform cover being treated by the machine;

Fig. 4 is an angular view, with parts broken away, of the work gripping rolls as embodied in a machine for applying cement of the solvent type and having a conical button work rest;

Fig. 5 is a vertical section through the cement roll and adjacent parts of Fig. 4 with a portion of a shoe held in an upright position as the adjacent part of the cover is cemented; and

Fig. 6 is a side elevation of similar work-engaging rolls in a machine of the type shown in Fig. 1 but provided with a conical work rest.

The invention, as illustrated in Figs. 1 to 3, is embodied in a cement-applying machine designed for latex-type cements, the machine being of the type shown in Fig. 6 of United States Letters Patent No. 1,851,162, granted March 29, 1932, upon an application filed on behalf of John W. Cosgrove, deceased. Such machines include an applying roll 10 which is mounted on the outer end of a shaft carried in bearings in a frame 12 and supplied with adhesive by means of a series of rolls including a pick-up roll 14 which dips in a trough 16 supplied from an inverted bottle 18. Pieces of work are presented to the under surface of the periphery of the applying roll 10 and are held in contact therewith by means of a coacting feed roll 20 journaled in an arm 22 which is pivoted in the frame and can be raised at the will of the operator to grip the work. Machines of this type were designed for and have been widely used for the application of cement to a flexible, loose piece of upper material or the like.

To facilitate the presentation of a flexible piece projecting from the periphery of the bottom of a shoe, the machine has been provided with a work-guide or work-rest abutment 24 which has a terminal surface at or in front of the unobstructed and free end of the applying roll 10. The abutment 24 preferably is vertically adjustable upon a T-shaped block 26, and the latter is horizontally adjustable upon an arm 28 which is attached to the frame 12 of the machine. The lower end of this abutment 24 provides a bevel faced supporting surface 30 against which the bottom of a shoe part 32 may be pressed to position the shoe as it is moved lengthwise or is rotated about a toe or heel end and serves to guide the work through the machine.

This shoe-bottom part 32 may be a wedge heel or a platform sole or, in the case of unlined uppers or moccasin work, it may be an insole. In the illustrated shoe S (Figs. 2 and 3) which is mounted upon a last L, an insole 34 is positioned inside of the platform sole 32 and is attached as by means of adhesive to a so-called "sock lining" 36, which is a characteristic portion of slip-lasted shoes. Attached by a seam 48 to this sock lining is the shoe upper 37 and also a peripheral band of flexible material which, in the illustrated shoe construction, constitutes a cover 38 for the periphery of the platform sole 32 and is intended to be lasted over the bottom surface 40 of that sole. Consequently, it is desired to apply adhesive to the inner margin 42 of the platform cover up

to a point close to the corner 44 of the platform sole so that the lasting margin will be coated with cement while, on the other hand, a clean margin of about one sixteenth of an inch short of the corner 44 will be left so that the cover 38 will not stick to the periphery of the sole and need to be pulled away before it can be lasted.

Attention is called to the shape of the bottom portion of the abutment 24 which is supported beside and at the unsupported end of roll 10. The abutment, being tapered toward the rear (Fig. 2) with respect to the direction of feeding movement, provides a bevel supporting or abutment surface 30 for the shoe bottom member 32 which is inclined with respect to and forms an acute angle with a plane normal to the axes of the rolls 10 and 20, when observed in horizontal section as in Fig. 2, and causes the margin of the cover 38 to be stretched as the shoe is wedged away from the rolls in an angular direction with respect to a "normal" direction of feeding movement which would be imparted by the rolls 10 and 20 if there were no such guide surface. It will be understood that this so-called "normal" direction is parallel to the end surfaces of the rolls and hence normal to their axes and in a substantially horizontal direction. Consequently, there is a "cross feed" action as the shoe is diverted from this normal direction so that the cover is stretched taut in a direction normal to its attaching seam 48 and permits the application of cement to a width of margin 42 which is substantially the same, making allowance for the spring-back of the material after the tension is relieved, as that which is to be lasted over the bottom 40 of the platform sole. The magnitude of this stretching force depends upon the angle of the taper of the supporting surface 30 and can be made very substantial. To avoid damaging the bottom 40 of the platform sole by inadvertent collision between it and the near corner of the roll 10, the guiding abutment 24 is extended at 46 (Fig. 2) to provide a guard for said roll.

The flexible material projecting along the periphery of the bottom of a lasted shoe which is to be presented to the machine may extend only around the forepart thereof or may extend around the whole of the periphery. In either case, the shoe will occupy an up-and-down position at least once during the traverse of the work and possibly twice. It is essential, therefore, that there shall be no interference between the bottom of the shoe and the other parts of the machine and, to facilitate the swinging of the work through this upright position, it will be noticed that the lower end of the abutment 24 is also tapered downwardly, as is indicated in the vertical section thereof shown in Fig. 3. As a consequence, the upper part of the work tilts away from the machine and is not likely to come in contact with it.

In presenting a piece of work to this machine, the shoe will be held horizontally with its bottom surface upright, and the marginal portion of the platform cover 38, for example, will be inserted between the ingoing peripheral surfaces of the rolls 10 and 20, and the roll 20 will be lifted to grip the work. The bottom surface 40 of the shoe will rest against the inclined surface 30 of the abutment 24 and, as the cement is applied to the margin 42 of the cover, the latter will be vigorously stretched away from its attaching seam 48 by a component pull which will be resisted by the supporting surface 30.

In the use of the type of machine illustrated in Figs. 4 and 5, and designed for use with a sol-

vent-type cement, the work is gripped between a grooved and corrugated cement-applying roll 50 and a work-supporting roll 52. The outer ends of these rolls are exposed and freely accessible. The arrangement, generally, is like that found in machines of the type illustrated in United States Letters Patent No. 1,380,360, granted June 7, 1921, upon the application of John W. Cosgrove, where the supply of cement is contained in a receptacle 54, and the cement roll 50 and associated parts are carried in a detachable block 56 which has a projecting stud 58 received in a socket in the frame 60 in which the receptacle is formed. Journalized in this frame, is a drive shaft 62 for the cement roll, and the end of the shaft is hollow and provided with projecting lugs 64 for coaction with the notches in a sleeve-like extension 66 integral with the applying roll 50. The quantity of cement carried out by the applying roll from a passage 68 extending between the receptacle 54 and the surface of the roll is controlled by a stripper 70 the position of which may be regulated by a screw 72 in a well-understood manner. A closure 74 for this passage 68 and to cover the end of the roll is attached to the frame 60 by screws 76 and extends over the near periphery of the cement roll to prevent contact of the cover with the applying roll 50 except at the bottom thereof. A shield 75 for the remainder of the periphery of the roll 50 is supported on the block 56.

At the end of the applying roll is a member rotatable therewith in the form of a conical button 80 which serves, substantially like the surface 30, as a bevel faced sole deflecting abutment or guide and is provided with a stud 82 received in the hollow end of the drive shaft and attached thereto by a threaded portion 84. At substantially the apex of this conical button work rest is a socket 86 for an attaching wrench.

In the use of this type of machine, the platform cover 38 will be gripped between the cement-applying roll and the driven supporting roll 52, and the bottom of the platform sole 32 will bear against the conical surface of this work rest 80 along a radial line in the sector of the lower quarter of the near side. The exact location of this line will vary as the periphery of the shoe is traversed just as is brought out in the case of the surface 30 in the form of the invention shown in Figs. 1 to 3. The result will be to impart a cross-feed action, as in the previously described machine arrangement, which will stretch the cover and apply to it a marginal band of cement one edge of which is separated from the corner of the platform sole by a clean margin determined by the thickness of the edge of the rest 80 plus the closure plate 74 plus a spacing washer 90, the latter being between the base of the conical work-rest button 80 and a shoulder 92 on the end of the applying roll 50. A nominal clearance between the washer 90 and the plate 74 (which clearance is much exaggerated in the drawing) avoids friction between rotating and stationary parts. These spacing washers 90 are of less diameter than the roll 50 and the base of the button 80 and thereby provide a groove between the two. One or more may be employed, according to the width of clean margin which is desired.

In Fig. 6, the invention is illustrated as applied to a machine of the latex type, such as is shown in Fig. 1, but, here, the work rest is in the form of a conical button 93 which is attached to the end of the applying roll 10a by means of a threaded

stud 94, and the base of the conical member 93 is separated from the end of the applying roll by means of one or more washers 96 which, with the button 93, determine the width of the clean margin between the band of cement and the corner of the platform sole. For convenience, a cover-guiding finger 98, supported upon the frame of the machine, is arranged to extend across the periphery of the applying roll 10a adjacent to the bite between that roll and the supporting roll 20a to pull out covers which may, because of scant material, tend to lie too close to the adjacent surface of the sole.

The presentation of the work in this machine will be the same as with the type of machine in Fig. 4 and the function of the work rest will be the same. Either machine is applicable to the uppers of unlined shoes and of certain moccasin uppers for cement lasting as well as to the covers of platform shoes and the mode of operation will be the same.

Having thus described my invention, what I claim as new and desire to secure by Letters Patent of the United States is:

1. In a cement applying machine for platform covers to be lasted over the adjacent bottom surfaces of platform soles, coacting rolls having their adjacent outer ends exposed and freely accessible to grip a platform cover as it projects beyond the platform sole, means for driving said rolls, means for supplying cement to one roll, and a work rest on one roll for contact with the bottom surface of the adjacent platform sole to guide the shoe bottom in a plane forming an acute angle with a plane normal to the axis of said rolls, thereby to cause the cover to be tensioned.

2. In a cementing machine for platform covers to be lasted over the adjacent bottom surfaces of platform soles, coacting cover-gripping rolls at least one of which is driven, means for supplying cement to one of the rolls, and a work-positioning member rotatable with the latter roll and positioned for contact with the adjacent surface of the platform sole.

3. In a machine for applying cement to the lasting margin, of shoe-upper material on a last, to be lasted over the adjacent surface of a shoe-bottom member, coacting rolls, at least one of which is driven, for gripping said margin, means for supplying cement to one of the rolls, and a conical button carried by the latter roll to provide a guide for engagement with the adjacent surface of the shoe-bottom member to deflect the latter away from the path of feeding movement determined by the margin-gripping rolls so as thereby to tension said margin.

4. In a cementing machine for platform covers to be lasted over the adjacent bottom surfaces of platform soles, coacting cover-gripping rolls at least one of which is driven, means for supplying cement to one of the rolls, and a work-positioning member in the form of a conical button carried by the latter roll at its exposed end for contact with the adjacent surface of the platform sole, the base of said button being spaced axially from the end of the applying roll thereby to provide a clean margin between the band of cement applied to the cover and the corner of the platform sole.

5. In a cementing machine for platform covers to be lasted over the adjacent bottom surfaces of platform soles, coacting cover-gripping rolls at least one of which is driven, means for supplying cement to one of the rolls, a work-positioning

conical button attached to the exposed end of the latter roll for contact with the adjacent surface of the platform sole, and a spacer of less diameter than the roll interposed between the base of said button and the end of the applying roll thereby to provide a groove between the applying roll and the button which will leave a clean margin between the band of cement applied to the cover and the corner of the platform sole.

6. In a cementing machine for platform covers to be lasted over the adjacent bottom surfaces of platform soles, coacting rolls, means for driving at least one of said rolls, said rolls being exposed and freely accessible at one end, a passage for supplying cement to the upper portion of one of the rolls defined at one side by a depending closure plate limiting the width of the band of cement applied by said roll, and a conical button on the end of the applying roll, there being a groove between the base of said button and the applying roll receiving a portion of said closure plate within the periphery of said roll thereby to determine a clean margin between the stripe of cement applied to the cover and the adjacent corner of the platform sole.

7. In a machine for applying cement to the lasting margin, of shoe-upper material on a last, to be lasted over the adjacent bottom surface of a shoe-bottom member, margin-gripping means for progressively cementing and feeding said margin, means for supplying cement to said means, and a bevel faced sole deflecting guide for wedging the sole away from the gripping means to tension the margin as it cements it.

8. In a machine for applying cement to the margin of flexible material disposed about at least part of the periphery of a partially completed shoe and extending beyond the bottom thereof, an applying roll supported for rotation at one end of a driven substantially horizontal shaft, a coacting work-supporting roll, means for supplying cement to the periphery of said first-named roll for application to the inner margin of the material, and a rest at the unsupported end of said applying roll having a surface against which the bottom of the shoe may be pressed to facilitate the guiding of the margin of the material in a direction other than normal to the axis of the applying roll to cause the material to be stretched as a coating is applied to its margin, a horizontal section through said axis intersecting said surface along a line lying at an acute angle to said axis.

9. In a machine for applying cement to flexible material disposed about at least part of the periphery of a partially completed shoe and extending beyond the bottom thereof, an applying roll supported for rotation at one end of a driven shaft, a coacting work-supporting roll, means for supplying cement to the periphery of said first-named roll for application to the inner margin of the material, and means, adjacent to the unsupported end of said applying roll, for engagement by the bottom of the shoe to position it in a plane forming an acute angle with a plane normal to the axes of said rolls, said latter means being operative to guide the margin of the material angularly with respect to the path of travel of a point on the periphery of the applying roll.

10. In a machine for applying cement to flexible material disposed about at least part of the periphery of a partially completed shoe and extending beyond the bottom thereof, an applying roll supported for rotation at one end of a driven shaft, a coacting work-supporting roll, means

for supplying cement to the periphery of said first-named roll for application to the inner margin of the material, and a guard for that corner of one of said rolls toward which the shoe is moved as the projecting material is coated, said guard providing also an abutment at the front end of the applying roll and against which the shoe may be pressed to facilitate guiding the marginal material angularly to produce a cross feed which will stretch the material as it passes between the rolls.

11. In a cementing machine, coacting rolls for gripping the margin of material projecting from the bottom of a shoe and intended to be lasted over that bottom, means for driving at least one of said rolls, means for supplying cement to the periphery of one of said rolls, whereby they feed the material and apply cement to a margin thereof, and shoe-bottom abutting means cooperating with said rolls concurrently acting to force the bottom of the shoe away from the roll end thereby to tension the material, said abutting means having a terminal surface at the end of one roll and providing a guide rest for the bottom of the shoe permitting free rotation of the shoe to present the material to the coating roll.

12. In a cementing machine, coacting rolls, unsupported at one end, for gripping the margin of material projecting from the bottom of a shoe and intended to be lasted over that bottom, means for driving one of said rolls, means for supplying cement to the periphery of one of said rolls for application to the inner margin of said projecting material, and an abutment in front of the unsupported end of the cementing roll, said abutment having an unobstructed, exposed work-engaging face for guiding the shoe bottom at an angle to the direction of feed imparted by the rolls and serving to cause the projecting material to be tensioned.

13. In a cementing machine, apparatus including coacting rolls for gripping the margin of material projecting from the bottom of a shoe and intended to be lasted over that bottom, said rolls being unsupported at their outer ends, means for driving at least one of said rolls, means for supplying cement to one of said rolls for application to one face of said margin, and a wedge-shaped abutment at the unsupported end of said applying roll, said abutment serving as a rest for the bottom of the shoe pressed against it and having a thin portion adjacent to the incoming work and a thick portion adjacent to the leaving portion of the work.

14. In a machine for applying cement to flexible material disposed about at least part of the periphery of a partially completed shoe and extending beyond the bottom thereof, a cement-applying roll mounted for rotation about a horizontal axis upon a shaft projecting laterally from one end of said roll, means for supplying cement to the periphery of said roll, a work-supporting roll coacting with the under side of said applying roll, and an abutment positioned adjacent to the unsupported end of said applying roll, said abutment being tapered rearwardly with respect to the direction of feeding movement imparted by said rolls and arranged to engage that portion of the bottom of the shoe over which the projecting material is later to be lasted and attached by the applied cement so as to require the feed of the work in such an angular relation to the normal pull or force exerted by the rolls, in their feeding capacity, as to stretch the part being coated.

15. In a machine for applying cement to flex-

ible material disposed about at least part of the periphery of a partially completed shoe and extending beyond the bottom thereof, a cement-applying roll mounted for rotation about a horizontal axis upon a shaft projecting laterally from one end thereof, means for supplying cement to the periphery of said roll, a work-supporting roll coacting with the under side of said applying roll, and a depending abutment positioned adjacent to the unsupported end of said applying roll, said abutment being tapered rearwardly and downwardly with respect to the direction of feeding movement imparted by said rolls and arranged to serve as a guide for that portion of the bottom of the shoe over which the projecting material is later to be lasted and attached by the applied cement.

16. In a coating machine for a platform shoe having a flexible platform cover surrounding the periphery of a platform sole on the shoe and extending at a sharp angle to the shoe bottom, a bevel faced sole-deflecting abutment, and cover-gripping and feeding means for also coating the inner margin of the cover, said means cooperating

with the abutment in also tensioning the cover away from the sole, said abutment being interposed between the coating means and the platform sole to space the band of coating material far enough from the corner of the sole to prevent contact of the coating material with the peripheral edge of the platform sole when the tension on the cover is relieved.
